UNITED STATES PATENT OFFICE

PRINCE D. CALDWELL, OF LOS ANGELES, CALIFORNIA

CENTRIFUGAL COMPRESSOR

Application filed November 25, 1930. Serial No. 498,158.

This invention relates to a centrifugal compressor which is particularly for use on refrigerating and ice making machines or apparatus, but it is to be understood, of course, that a compressor in accordance with this invention may be used with any kind of apparatus for which the same is found adapted and desirable.

An important object of the invention is to provide, in a manner as hereinafter set forth, a centrifugal compressor of the aforementioned character embodying a plurality of connected fluid impelling or driving units of the centrifugal type wherein no valves are necessary.

Another important object of the invention is to provide a centrifugal compressor of the character described embodying a novel construction and arrangement of fluid impelling units together with novel means for preventing leakage of the fluid from the compressors.

Other objects of the invention are to provide a centrifugal compressor for refrigerating and ice making machines which will be simple in construction, strong, durable, highly efficient in operation and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:—

Figure 1 is a view in side elevation of a compressor constructed in accordance with this invention.

Figure 2 is a vertical longitudinal sectional view through one of the water cooled centrifugal fluid impelled units.

Figure 3 is a view in vertical longitudinal section through the forwardmost centrifugal impeller unit which is not provided with water cooling means.

Figure 4 is a vertical cross sectional view taken substantially on the line 4—4 of Figure 2.

Figure 5 is a vertical cross sectional view

taken substantially on the line 5—5 of Figure 1.

Referring to the drawings in detail, and to Figure 1 in particular, it will be seen that the reference numeral 1 designates a suitable base upon the opposite end portions of which are mounted the standards 2 having suitable bearings 3 on their upper ends in which are journaled for rotation the opposite end portions of an elongated, horizontally disposed shaft 4 having fixed on one end portion a suitable coupling 5 for connecting the shaft 4 with the shaft of an electric motor (not shown) or other suitable source of power for actuation. The base 1 and the shaft 4 may be of any desired length, as will be apparent.

Longitudinally aligned housings 6, 7, 8, 9, and 10 are mounted vertically on the base 1 between the standards 2 through the medium of the integral supporting feet 11 having the out-turned apertured flanges 12 on their lower ends for the passage of suitable anchoring bolts or the like 13. The shaft 4 extends centrally through all of the housings. Each of the housings comprises upper and lower half sections provided with apertured flanges for bolting the sections together with a suitable gasket between them. Housings 8, 9, and 10 are provided with jackets 14 to provide water circulating spaces 15 which are connected with each other and with a suitable source of water supply by the pipes 16. In this manner the fluid impelling units of which the housings 8, 9 and 10 are a part are water cooled. Fixed on the shaft 4 for rotation therewith in each of the housings 3 to 10, inclusive, is a centrifugal fluid impeller 17 having a centrally disposed chamber 18 with which a fluid intake opening 19 communicates on one side of the impeller 17. Fluid passages 20 radiate from the central chamber 18 and extend to the periphery of the impeller 17. As will be seen the impeller 17 has its front and rear walls and its periphery spaced inwardly from the corresponding walls and the periphery of the housing.

Each impeller 17 is provided with an integral hub portion 21 which projects into the central chamber 18. As will be apparent, the hub 21 supports the impeller on the shaft 4

and is provided with a longitudinal groove which registers with the longitudinal groove 22 provided in the shaft 4 for the reception of a key 23 for securing the impeller 17 to the shaft 4 against rotation. It is understood, of course, that the shaft 4 is provided with a groove or key-way 22 for each of the housings 6 to 10, inclusive. Each of the hubs 21 of the impellers 17 has threaded thereinto 10 a set screw 24 for engagement with the key 23 for securing said key against longitudinal movement in the groove or keyway 22.

The forward side of each of the housings 6 to 10, inclusive, is provided with a centrally disposed opening of materially greater diameter than the shaft 4 and projecting through said opening is an annular flange 25 formed integrally with the forward side of the impeller 17 and disposed in spaced concentric relation to the shaft 4. The diameter of the flange 25 is greater than that of the fluid intake opening 19 of the impeller 17 and thus an internal flange 26 is provided which is disposed in spaced concentric relation to the shaft 4 for providing the fluid intake opening 19.

A supporting bracket 27 rises from the base 1 between the housing 6 and the adjacent standard 2 and supports, on its upper end, 30 the fluid intake conduit 28 through which the shaft 4 extends longitudinally and which is spaced concentrically from the shaft 4 in a manner to provide a fluid passage 29 having one end in communication with the fluid intake opening 19 in the impeller 17. A fluid inlet 30 extends upwardly from the intermediate portion of the conduit 28 for connection with a suitable fluid supply pipe (not shown). The conduit 28 extends longitudinally into the flange 25 in spaced, concentric relation to said flange 25 and terminates adjacent the flange 26. An extension 31 projects forwardly from the conduit 28 in spaced, concentric relation to the shaft 4 and mounted therein are suitable packing rings 32 between groups of which is mounted an oil lantern 33. A port 34 is provided for lubricating the shaft 4 at this point. A packing adjusting nut or gland 35 is threaded 45 into the extension 31 for compressing the packing rings 32 when it is so desired.

Each of the housings 6 to 10, inclusive, is provided, on its forward side, with an integral, forwardly projecting neck 36 which is disposed in spaced concentric relation to the flange 25 on the impeller 17 and the neck 36 is provided with an out-turned, integral apertured flange 37 on its free end portion. Suitable packing rings 38 of compressible material are mounted between the neck 36 and the flange 25 and suitable oil lanterns 39 are disposed between groups of the packing rings 38. An oil port 40 is provided for lubricating the outer periphery of the flange 25 when the machine is in operation. Pack-

ing rings 41 of suitable compressible material are disposed between the flanges 25 and the fluid intake conduit 28 of each unit and an oil lantern 42 is disposed between groups of the packing rings 41. Stop rings 41' are threaded on the intake conduits 28 for retaining the packing rings 41 thereon. A duct 43 is provided in the fluid intake conduit 28 to permit lubricating oil to be forced by any suitable means between the flange 25 and the conduit 28 for lubricating the inner periphery of the flange 25.

An internally threaded annulus 44 is rigidly mounted in forwardly spaced relation to the flange 37 through the medium of the screws 45 upon which are mounted the spacing collars 46 which are interposed between the flange 37 and the annulus 44. The inner periphery of the annulus 44 is disposed in spaced, concentric relation to the fluid intake conduit 28 and threaded into said annulus for longitudinal adjustment on the conduit 28 is a compressing flange or nut 47 which is engageable with the packing rings 41 for compressing the same to the desired degree.

The annulus 44 has its forward side recessed to rotatably receive an internally toothed ring gear 48 which is retained rotatably in position by a suitable retaining ring 49 which is threaded into the recess provided in the annulus 44 for the ring gear 48. A packing compressing ring 50 extends between the free end portions of the neck 36 and the flange 25 for longitudinal adjustment and is engageable with the packing rings 38 for compressing the same when it is so desired. Threaded at spaced points into the side of the compressing ring 50 which is free of the packing rings 38 are a plurality of threaded shanks 51 which are journaled transversely through the annulus 44 and are retained against longitudinal movement relative to the annulus 44 by the flanges 52 which are fixed on the shanks 51 and engageable with one side of the annulus 44 and the gears 53 which are fixed on the shanks 52 and engageable with the other side of the annulus 44. The gears 53 are in mesh with the ring gear 48. Polygonal heads 54 are fixed on the outer portions of the shanks 51 for receiving a suitable actuating tool such as a wrench for rotating the shanks 51.

It will thus be seen that when one of the shanks 51 is rotated, the remaining shanks 51 are simultaneously rotated to move the compressing ring 50 toward or away from the packing rings 38.

The housings 6 to 10, inclusive, are connected with each other by the conduits 55 which are identical in construction and arrangement with the fluid intake conduit 28 with the exception that their forward ends are secured, as by bolts or the like 56 to the forwardly adjacent housing, the bolt 56 passing through apertured flanges 57 formed

integrally on the conduits 55 and anchored in said forwardly adjacent housings. The intake opening 30 and the elements 31 to 35 which are associated with the fluid intake 5 conduit 28 are, of course, eliminated from the unit connecting conduits 55. The conduits 55 are, of course, spaced, concentrically from the shaft 4. The rear side of each of the housings 6 to 9, inclusive, is provided with a 10 fluid outlet opening 58 in communication with the unit connecting conduits 55. A suitable packing gland 59 is provided on the rear wall of the rearmost housing 10 through which the shaft 4 extends for preventing 15 leakage of the fluid at this point. The packing unit 59 is preferably similar in construction to the packing unit comprised by the elements 31 to 35, inclusive. The rearmost housing 10 is provided with an upstanding 20 gas outlet neck or opening 60 which is at one side of the rearmost housing and is provided with a suitable flange on its upper end for connection with a discharge pipe (not shown).

25 As best seen in Figure 4 of the drawings, the oil lanterns 39 and 42 have their side walls provided with holes 61 to receive a suitable tool for removing said lanterns when it is so desired. All of the oil lanterns which 30 are used in the machine are provided with these holes.

In operation, the fluid enters the intake conduit 28 through the intake opening 30 and passes through the passage 29 and 35 through the opening 19 into the central chamber 18 of the rotary centrifugal impeller 17 in the first housing 6. When the shaft 4 is rotating and thus driving the impeller 17 the fluid will be thrown by centrifugal force 40 through the radiating passages 20 against the inner periphery of the housing 6 and will then pass inwardly between the rear wall of the impeller 17 and the rear wall of the housing 6 and escape through the outlet opening 45 58 into the unit connecting conduit 55 and pass through the next impeller unit of which the housing 7 is an element. The operation is then repeated until the fluid reaches the housing 10, where said fluid is expelled 50 through the outlet opening or neck 60 into a suitable conduit or pipe (not shown). The housings 6 to 10, inclusive, are provided with removable drain plugs 63 in their lower portions. Suitable lubricating means 55 (not shown) may be provided on the bearings 3 for the shaft 4. It will also be understood that any desired number of the fluid impelling units may be provided.

60 It is believed that the many advantages of a compressor in accordance with this invention will be readily understood, and although the preferred embodiment of the invention is as illustrated and described, it is to be understood that changes in the details of con-

struction may be had which will fall within the scope of the invention as claimed.

What is claimed is:—

1. A compressor of the character described comprising a base, a series of longitudinally aligned impeller units mounted on the base, a rotary shaft extending longitudinally through the units, each unit including a housing having a centrally disposed fluid inlet opening in one side and a centrally disposed fluid outlet opening in its opposite side, conduits connected to the respective outlet openings and extending between the housings for passing the fluid therebetween, the shaft passing through the openings and conduits in spaced, concentric relation thereto, an integral neck extending longitudinally from the forward side of each housing in spaced, concentric, surrounding relation to the adjacent conduit, a centrifugal impeller fixed on the shaft for rotation in each housing and spaced therefrom, an integral flange extending longitudinally from one side of the impeller between the neck and the conduit in spaced concentric relation to said neck and conduit, and sealing means between the flange and the neck and between the flange and the conduit. 70

2. A compressor of the character described comprising a base, a series of longitudinally aligned impeller units mounted on the base, a rotary shaft extending longitudinally 75 through the units, each unit including a housing having a centrally disposed fluid inlet opening in one side and a centrally disposed fluid outlet opening in its opposite side, conduits connected to the respective outlet openings and extending between the housings for passing the fluid therebetween, the shaft passing through the openings and conduits in 80 spaced, concentric relation thereto, an integral neck extending longitudinally from the forward side of each housing in spaced, concentric, surrounding relation to the adjacent conduit, a centrifugal impeller fixed on the shaft for rotation in each housing and spaced therefrom, an integral flange extending longitudinally from one side of the impeller between the neck and the conduit in spaced concentric relation to said neck and conduit, and sealing means between the flange and the neck and between the flange and the conduit. 85

2. A compressor of the character described comprising a base, a series of longitudinally aligned impeller units mounted on the base, a rotary shaft extending longitudinally 90 through the units, each unit including a housing having a centrally disposed fluid inlet opening in one side and a centrally disposed fluid outlet opening in its opposite side, conduits connected to the respective outlet openings and extending between the housings for passing the fluid therebetween, the shaft passing through the openings and conduits in 95 spaced, concentric relation thereto, an integral neck extending longitudinally from the forward side of each housing in spaced, concentric, surrounding relation to the adjacent conduit, a centrifugal impeller fixed on the shaft for rotation in each housing and spaced therefrom, an integral flange extending longitudinally from one side of the impeller between the neck and the conduit in spaced concentric relation to said neck and conduit, and sealing means between the flange and the neck and between the flange and the conduit. 100

3. A compressor of the character described comprising a base, a series of longitudinally aligned impeller units mounted on the base, a rotary shaft extending longitudinally 105 through the units, each unit including a housing having a centrally disposed fluid inlet opening in one side and a centrally disposed fluid outlet opening in its opposite side, conduits connected to the respective outlet openings and extending between the housings for passing the fluid therebetween, the shaft passing through the openings and conduits in spaced, concentric relation thereto, an integral neck extending longitudinally from the forward side of each housing in spaced, concentric, surrounding relation to the adjacent conduit, a centrifugal impeller fixed on the shaft for rotation in each housing and spaced therefrom, an integral flange extending longitudinally from one side of the impeller between the neck and the conduit in spaced concentric relation to said neck and conduit, and sealing means between the flange and the neck and between the flange and the conduit. 110

4. A compressor of the character described comprising a base, a series of longitudinally aligned impeller units mounted on the base, a rotary shaft extending longitudinally 115 through the units, each unit including a housing having a centrally disposed fluid inlet opening in one side and a centrally disposed fluid outlet opening in its opposite side, conduits connected to the respective outlet openings and extending between the housings for passing the fluid therebetween, the shaft passing through the openings and conduits in spaced, concentric relation thereto, an integral neck extending longitudinally from the forward side of each housing in spaced, concentric, surrounding relation to the adjacent conduit, a centrifugal impeller fixed on the shaft for rotation in each housing and spaced therefrom, an integral flange extending longitudinally from one side of the impeller between the neck and the conduit in spaced concentric relation to said neck and conduit, and sealing means between the flange and the neck and between the flange and the conduit. 120

5. A compressor of the character described comprising a base, a series of longitudinally aligned impeller units mounted on the base, a rotary shaft extending longitudinally through the units, each unit including a housing having a centrally disposed fluid inlet opening in one side and a centrally disposed fluid outlet opening in its opposite side, conduits connected to the respective outlet openings and extending between the housings for passing the fluid therebetween, the shaft passing through the openings and conduits in spaced, concentric relation thereto, an integral neck extending longitudinally from the forward side of each housing in spaced, concentric, surrounding relation to the adjacent conduit, a centrifugal impeller fixed on the shaft for rotation in each housing and spaced therefrom, an integral flange extending longitudinally from one side of the impeller between the neck and the conduit in spaced concentric relation to said neck and conduit, and sealing means between the flange and the neck and between the flange and the conduit. 125

the same, a plurality of shanks journaled transversely for rotation through the annulus and having one end portion threaded into the ring in a manner to shift said ring longitudinally upon rotation of the shanks and flanges on the shanks engaged with the annulus for retaining said shanks against the longitudinal movement in one direction.

3. A compressor of the character described comprising a base, a series of longitudinally aligned impeller units mounted on the base, a rotary shaft extending longitudinally through the units, each unit including a housing having a centrally disposed fluid inlet opening in one side and a centrally disposed fluid outlet opening in its opposite side, conduits connected to the respective outlet openings and extending between the housings for passing the fluid therebetween, the shaft passing through the openings and conduits in spaced, concentric relation thereto, an integral neck extending longitudinally from the forward side of each housing in spaced, concentric, surrounding relation to the adjacent conduit, a centrifugal impeller fixed on the shaft for rotation in each housing and spaced therefrom, an integral flange extending longitudinally from one side of the impeller between the neck and the conduit in spaced concentric relation to said neck and conduit, and sealing means between the flange and the neck and between the flange and the conduit, said means comprising an internally threaded annulus rigidly supported in spaced relation to the free end of the neck and disposed in spaced, concentric relation to the conduit, a gland encircling the conduit and threaded through the annulus for longitudinal adjustment between the flange and the conduit, packing rings disposed between the flange and the conduit for engagement and compression by the flange, packing rings disposed between the flange and the neck, a ring adapted for longitudinal movement between the flange and the neck and engageable with the last named packing rings for compressing the same, a plurality of shanks journaled transversely for rotation through the annulus and having one end portion threaded into the ring in a manner to shift said ring longitudinally upon rotation of the shanks, and flanges on the shanks engaged with the annulus for retaining said shanks against the longitudinal movement in one direction, gears fixed on the shanks, and an internally threaded ring gear mounted for rotation in the annulus, said ring gear meshing with the gears on the shanks and constituting means for operatively connecting the shanks together for simultaneous rotation.

In testimony whereof I affix my signature.
PRINCE D. CALDWELL.
